CLAIM

The ornamental design for a skylight dome, as shown and described.

DESCRIPTION

FIG. 1 is a perspective view of a skylight dome;
 FIG. 2 is a top view of the skylight dome of FIG. 1;
 FIG. 3 is a front view of the skylight dome of FIG. 1;
 FIG. 4 is a rear view of the skylight dome of FIG. 1; and,
 FIG. 5 is a first side view of the skylight dome of FIG. 1, the
 second side being a mirror image of the first side view.

1 Claim, 5 Drawing Sheets(56)
